[57] CLAIM

The ornamental design for a door positioning hinge, as shown and described.

DESCRIPTION

FIG. 1 is a perspective view of a door positioning hinge embodying my design;

FIG. 2 is a front elevational view thereof;

FIG. 3 is a left side elevational view thereof, the right side being a mirror image of that shown;

FIG. 4 is a top plan view thereof; and,

FIG. 5 is a bottom plan view thereof.

The broken-line disclosure of a portion of a surface are for illustrative purposes only and forms no part of the claimed design.
